(57) **CLAIM**

The ornamental design for a portable electronic device case, as shown and described.

DESCRIPTION

FIG. 1 is a front view of a portable electronic device case showing my new design.

FIG. 2 is a back view thereof.

FIG. 3 is a front perspective view thereof.

FIG. 4 is a rear perspective view thereof.

FIG. 5 is a left side view thereof.

FIG. 6 is a right side view thereof.

FIG. 7 is a top side view thereof; and,

FIG. 8 is a bottom side view thereof.

The broken lines immediately adjacent the shaded surfaces represent boundaries of the claimed design. All other broken lines depict unclaimed environment. The broken lines form no part of the claimed design.
